UNITED STATES PATENT OFFICE.

VICTOR E. LANE, OF DETROIT, MICHIGAN.

ANNEALING-FURNACE.

1,292,617.

Specification of Letters Patent. Patented Jan. 28, 1919.

Application filed April 18, 1916. Serial No. 229,265.

To all whom it may concern:

Be it known that I, VICTOR E. LANE, a citizen of the United States of America, residing at Detroit, in the county of Wayne and State of Michigan, have invented certain new and useful Improvements in Annealing-Furnaces, of which the following is a specification, reference being had therein to the accompanying drawings.

10 The invention relates to furnaces designed for annealing or otherwise heat-treating metal, and it is the object of the invention to prevent the corrosion of the surface of the work through contact with atmosphere containing free oxygen. It is a further object to provide means for easily inserting and withdrawing the work without breaking the seal. With these objects in view the invention comprises the novel features as 20 hereinafter set forth.

In the drawings:

Figure 1 is a sectional plan view of the furnace;

Fig. 2 is a vertical longitudinal section 25 thereof; and

Fig. 3 is a transverse section.

When iron, steel and other common metals are subjected to a temperature sufficient for annealing they are readily oxidized and if 30 exposed to an atmosphere containing free oxygen will become covered with a scale. On the other hand, if such metals during heat-treatment may be maintained in a reducing or a neutral atmosphere such corrosion is prevented. It is possible to construct a muffle or oven chamber which is sufficiently air-tight to retain a neutral or reducing atmosphere, but the difficulty is to provide any means of readily inserting and withdrawing 35 the work without exposure to oxidation.

40 My improved construction overcomes this difficulty and comprises essentially a muffle chamber which is open at the bottom, but has such opening water-sealed; also means 45 for introducing the work through the water-sealing for raising it into the heated chamber and finally lowering it into the water and withdrawing it. In detail, A is the exterior wall of the furnace and B is a muffle 50 arranged therein, being supported upon a base C having an opening D therein substantially the size of the interior dimensions of the muffle. Beneath the base C is a pit E and extending laterally from this pit be-

55 neath the base is a tunnel F having at its opposite ends upwardly-inclined portions G

and G'. The preferred level of water in the pit and tunnel is, as indicated by the broken line in Fig. 2, intermediate the top and bottom of the base C. Within the pit is arranged a work-supporting table H together with mechanism for raising and lowering the same, which as shown comprises the hydraulic jacks I therebeneath. The construction is such that by the operation of the raising means the table H may be lifted so as to be above the water seal and form a bottom for the muffle, while in its lowered position this table lies flush with the bottom of the tunnel. The upper face of the table 70 is preferably corrugated or provided with a series of points which permit the water to easily drain off and which will limit the surface contact with the work.

With the construction as described heat within the combustion chamber is obtained by any suitable means and the muffle is heated thereby to the desired temperature. The space within the muffle is cleared from free oxygen by the displacement of steam 80 or a neutral gas, and the water-seal prevents access of the external atmosphere. When the proper temperature is attained the work to be heat treated is slid down one of the inclined ends of the tunnel and pushed inward upon the table H. The jacks I are then operated to lift the table, which carries the work upward above the water seal and into the heated chamber. After the completion of the heat treatment the table 85 is again lowered, which will plunge the heated work into water and will cool the same to a temperature below the oxidizing point. The work may then be withdrawn through the opposite end of the tunnel and new work introduced in the manner before described.

The construction will be particularly useful in the annealing of cold drawn or pressed metal, such operation being necessary intermediate successive drawing or pressing operations. Under the usual practice it is necessary after such an annealing operation to remove the scale from the work either by pickling in an acid bath or other 105 means, but when heat treated in my improved furnace the formation of scale is prevented.

What I claim as my invention is:

1. The combination with a furnace, of a muffle therein open at its bottom, means for water-sealing the open end of said muffle,

a work-supporting table in registration with said muffle, means for raising and lowering said work-supporting table through said water-seal, and a tunnel extending beneath 5 said furnace and below the water-seal permitting the insertion and withdrawal of the work.

2. The combination with a furnace, of a muffle therein open at its bottom, a base for 10 supporting said furnace and muffle having a registering opening, means for water-sealing the opening in said base, a table registering with the opening in said base and muffle, means for raising and lowering said 15 table through the water-seal, the lowered position of said table being beneath said base, and a tunnel extending beneath said base and having its bottom substantially flush with the top of said table when in 20 lowered position, said tunnel forming means for introducing and withdrawing the work beneath the water-seal.

3. The combination with a furnace, of a muffle therein open at its bottom, a base for 25 supporting said furnace and muffle having a

registering opening, a pit beneath and registering with the opening in said base and muffle, a table and raising and lowering mechanism therefor located in said pit, and a tunnel beneath said base laterally communicating with said pit, said pit and tunnel being filled with water to a level which seals the opening through said base. 30

4. The combination with a furnace, of a muffle therein open at its bottom, a base for 35 supporting said furnace and muffle and having a registering opening therethrough, a pit beneath the opening in said base, a tunnel extending laterally beneath said base communicating with said pit, and having, 40 upward inclinations at its opposite ends, a table in said pit, and means also within said pit for raising and lowering said table, the lowered position being substantially flush with the bottom of said tunnel and the upward position being above the water-seal and so as to hold the work thereon in the muffle chamber. 45

In testimony whereof I affix my signature.
VICTOR E. LANE.
